UNITED STATES PATENT OFFICE.

CHARLES G. ABBOT, OF WASHINGTON, DISTRICT OF COLUMBIA.

SELF-PROPELLED PROJECTILE.

1,380,172.

Specification of Letters Patent. Patented May 31, 1921.

Application filed January 11, 1919. Serial No. 270,687.

To all whom it may concern:

Be it known that I, CHARLES G. ABBOT, a citizen of the United States of America, residing at Washington, in the District of Columbia, have invented certain new and useful Improvements in Self-Propelled Projectiles, of which the following is a specification.

My invention relates to improvements in projectiles, and it consists in the combinations, constructions and arrangements herein described and claimed.

An object of my invention is to provide a projectile which is designed to be used with smooth-bore guns, and which has a chamber containing a propelling medium, such as powder, with bores or passages tangent to the walls of the chamber and extending to the rear of the projectile in such a manner that when the propellant within the chamber is ignited the rush of gases through these passages propels the projectile forwardly, and at the same time causes the rotation of the projectile while in the gun, thus utilizing the full effect of the gases.

A further object of my invention is to provide a self-propelled projectile of the type mentioned in which means is provided for preventing a circulatory movement of the gases within the chamber which contains the propellant, thus increasing the reactive force of the gases.

A further object of my invention is to provide a projectile containing therein a propellant, the walls of the projectile itself aiding in resisting the bursting effect of the charge, and thereby permitting the use of the projectile in smooth-bore guns of relatively light weight, since the propelling force, in addition to being resisted by the walls of the projectile, is applied gradually and not suddenly, as in the case of the ordinary projectile, which is discharged by propellants contained entirely within the gun.

Other objects and advantages will appear in the following specification, and the novel features of the invention will be particularly pointed out in the appended claims.

My invention is illustrated in the accompanying drawings, forming part of this application, in which;

Figure 1 is a sectional view through one form of the projectile and through a portion of a smooth-bore gun;

Fig. 2 is a rear view of the projectile;

Fig. 3 is a view partly in section, of the projectile as used in a trench mortar;

Fig. 4 is a side view of a modified form of the device, the rear part being shown in section;

Fig. 5 is a rear view of the projectile shown in Fig. 4; and

Fig. 6 is a section along the line 6—6 of Fig. 4.

A number of attempts to produce the rotation of projectiles for use with smooth-bore guns, have been made. In each instance, as far as I am aware, these attempts have failed where such projectiles have been used as ordnance, due to the fact that the projectiles have been constructed so that the rotative force could be applied while the projectile is in flight. In certain instances, attempts have been made to obtain the rotative effect by air resistance. In other devices, the kinetic energy of the discharging gases has been used to produce a turbine effect. In such devices it has been necessary to construct spiral grooves and the difficulties of proportioning these grooves, as well as the cost of manufacturing projectiles of this type, have rendered these devices impractical.

The present invention relates to a projectile for use with smooth-bore guns in which the full force of the propellant contained within the projectile is utilized in propelling the projectile forwardly, and in rotating it while within the gun. Referring now to the drawings, 1 indicates the gun which is provided with a smooth bore 2 and, in the present instance, with a priming passage 3. In Fig. 1, the projectile illustrated is a shell 4, having a chamber 5 for the bursting charge, and a chamber 6 for the propellant. Any suitable means may be used for igniting the bursting charge. At 7 I have indicated an igniting device which may be a time fuse, a centrifugally operated igniter, or any other suitable ignition means.

The chamber 6 is closed by means of a screw plug 8, which fits in a threaded opening 9, at the rear of the projectile. This screw plug may contain any suitable means for igniting the propellant within the chamber 6, as for instance, a percussion cap 10, which may communicate by means (not shown) with the propellant.

Extending rearwardly from the chamber 6 are passages 11. These passages are ar-

ranged tangentially to the walls of the chamber 6, *i. e.*, they are tangent to a circle whose center is in the axis of the shell. The passages 7 are preferably enlarged at their rear ends to permit the free discharge of the gases therethrough. Within the chamber 6 are disposed baffles 12. In Fig. 1, these baffles are shown arranged with respect to the longitudinal axis of the projectile and preferably in alignment with the bores or passages 11. These baffles are for the purpose of breaking up the circulation of the gases within the chamber 6 which would tend to reduce the effectiveness of the propelling force were such circulation permitted.

From the foregoing description of the various parts of the device, the operation thereof may be readily understood. The projectile with its charge of propellant 13 is placed in the smooth-bore gun. When the propellant is ignited as, for instance, by means of a priming charge introduced through the priming passage 3, the gases 5 passing rearwardly through the bores 11 generate a pressure which drives the projectile forwardly and at the same time the projectile is rotated on its axis while within the gun. The charge of propellant is proportioned so that its force is expended before the projectile leaves the gun, the pressure tending to drive the projectile forwardly is developed gradually and during this development of the pressure the walls 5 of the projectile itself tend to resist lateral forces. For these reasons a projectile of this type, *i. e.*, a self-propelled projectile, may be used in a smooth-bore gun of much lighter weight than when the propelling charge is disposed entirely outside of the projectile. This is an important advantage, especially as far as the slow development of the propelling force is concerned. It will be noted that there are no passages which 5 extend to the front of the projectile or to the sides thereof. All of the force which propels the projectile forwardly is from the rear. In this respect the present invention differs from others which contain no propellant in the projectile itself. In the present instance use is made of all of the force generated.

It is also highly desirable in order to obtain the maximum force of the gases that 5 the bores 11 be conical shaped or enlarged

toward their rear ends. I have found, by experiment, that unless baffles are used within the chamber to provide resistance elements, the maximum propelling and rotating force cannot be attained.

In Figs. 4 to 6 inclusive, I have shown a modified form of the device in which the projectile 4' is provided with a chamber 6', having baffles 12', which are disposed longitudinally with respect to the axis of the 65 projectile instead of transversely. In this form of the device, that is to say, in the form disclosed in Figs. 4, 5 and 6, I have made use of additional bores 11'. Any suitable number, however, may be used. In 70 this instance, the plug 8' is not provided with an igniting means, the bores 11' being designed to furnish means for igniting the propellant within the chamber 6'.

My improved projectile is especially 75 adapted for use with trench mortars. In Fig. 3, I have illustrated a trench mortar 15 into which a projectile 16 has been dropped. The propellant within the projectile is designed to be actuated by the striking of the 80 cap 10' against the interior bottom of the mortar. The projectile is discharged and is rotated to insure true flight in the manner already described.

I claim:

1. A self-propelled projectile, having a chamber, a propellant disposed within the chamber, the body portion of the projectile having a bore tangent to the chamber wall, and terminating at the rear end of the projectile, and a baffle within the chamber for preventing circulatory currents therein.

2. A self-propelled projectile, having a chamber, the body portion of the projectile being provided with a bore extending from 95 the chamber to the rear end of the projectile, said bore being enlarged toward the rear end and being tangent to the walls of the chamber, and means within the chamber for preventing circulatory currents therein.

3. A self-propelled projectile, having a chamber, the body portion of the projectile being provided with a plurality of cone-shaped bores extending from the chamber to the rear end of the projectile, said bores 105 being tangent to the walls of the chamber, and a plurality of baffles within the chamber for preventing circulatory currents therein.

In testimony whereof I affix my signature.
CHARLES G. ABBOT.
